UNITED STATES PATENT OFFICE.

JOHN E. BELL, OF BROOKLYN, NEW YORK, ASSIGNOR TO POWER SPECIALTY COMPANY, OF NEW YORK, N. Y., A CORPORATION OF NEW YORK.

OIL HEATER FOR TOPPING STILLS.

1,418,272.

Specification of Letters Patent. Patented June 6, 1922.

Application filed June 10, 1920. Serial No. 387,970.

To all whom it may concern:

Be it known that I, JOHN E. BELL, a citizen of the United States, residing at Brooklyn, county of Kings, and State of New York, have invented certain new and useful Improvements in Oil Heaters for Topping Stills, of which the following is a full, clear, and exact description.

In the art of heating volatile oils in which the oil is passed through tubes or pipes exposed to a current of hot gases, and commonly known as pipe heaters for topping stills, the conditions best adapted for practical working and the attainment of the best results have not, by any means, been developed to the desired degree. Such devices are either uneconomical in fuel consumption or expensive in construction, largely if not mainly because the oil is not subjected to a uniform and progressive increase in temperature, due to the difficulty of obtaining the proper gas flow over the heating surface.

For example, in the topping stills that are now in use the oil is exposed to heat in pipes extending across a furnace and no attempt is made to baffle the hot gases so that they will pass over all the heating surface and at a high velocity.

Again, in some of these devices in an attempt to protect the lower row of tubes, the cold oil is pumped into this lower row where it is exposed to a higher gas temperature and from this point on there is an upward flow of the oil into the drum. An attempt to secure a flow of oil through the tubes counter to the flow of the hot gases, has required that the oil be pumped into the tubes at the top of the bank and the hot oil run off at the bottom, but this arrangement, however, is not satisfactory because any vapors that would form in the tubes must rise against the flow of the oil.

This problem I have studied and by the apparatus upon which is based my present application for Letters Patent I have succeeded in overcoming many of the objections which have been heretofore attached to devices of this character. I have designed, therefore, an apparatus which insures a proper gas pass over all the heating surface and at a sufficiently high velocity to insure the rapid and proper absorption of heat. I also propose to use an arrangement which, in addition to securing the proper gas pass, has also the advantage of a coun-

ter current flow, and which, moreover, permits the oil to travel always upward so that the vapors may separate in the tubes and travel with the oil. In my improved apparatus the tubes exposed to the hotter gas do not contain the hottest oil throughout, but do so to a sufficient extent for good practical results and in this respect the arrangement is a compromise between the two different plans outlined above as characteristic of present day topping stills.

In illustration, let it be assumed that an oil of relatively slight viscosity is to be distilled; the present forms of apparatus are not well adapted to its treatment. This is, of course, a special case, but as my present device is primarily designed to meet it, I shall describe it as used for such purpose, as in addition to the special features which I have devised for this purpose, the desirability of the other features for general, as well as for this special use, will be observed and appreciated.

In general terms, my improved apparatus comprises two chambers usually and preferably divided by a vertical wall or partition, the first leading up from the furnace or source of heat, the other at its end remote from the first connecting with the flue or stack.

In the second chamber are arranged a plurality of tubes for oil which, in the case of a still for an oil of relatively slight viscosity, are of relatively small diameter and preferable, connected in vertical series in multiple with upper and lower headers. The upper header leads to the bottom of a bank of special tubes in the upper part of the first chamber, which latter are connected in series between such header and an outlet header at the top.

As the row of tubes at the bottom of this second bank, or for safety's sake, if need be, the two lowermost rows of such tubes, are exposed not only to the radiant heat, but also to the very hot gases immediately above the fire, these tubes are enveloped in cast-iron casings of less thickness or weight per lineal foot than the remaining tubes of the bank, in order that they may absorb less of the heat and so not subject the oil passing through them to too great a heating effect. The other tubes of the bank, on the other hand, have cast-iron envelopes of greater surface, whereby for a given and lesser tem-

85

110

perature they will absorb a correspondingly greater amount of heat.

- The oil for this device is introduced under the proper pressure to the bottom header of the first bank, and is then led to the bottom header of the second bank. From this it results that in the primary heating of the oil in the first bank, an absolutely perfect counter-current of oil flow to gas flow is secured.
- 10 This counter-current principle is not maintained in the second bank and is not necessary, for by the time the oil reaches the second bank it is heated to a degree which makes the counter-current effect unnecessary to efficient and economical operation.

The tubes of the first bank need not be of any special character, that is to say, no special means are required to protect them from the destructive effects of the hot gases, as 20 the latter, by the time they have swept the second bank and reached the tubes of the first have parted with enough of their heat to render their action on the first bank of tubes harmless.

25 I prefer, however, to enclose all tubes in casings or envelopes composed of cast iron rings for two purposes: First, because such envelopes prevent the tubes from bulging, and the usual breakdown are due to such 30 bulges which subsequently crack; and, second, the corrugated form of the rings increases the heating surface of the tube very materially and makes a more compact structure.

35 This improvement is illustrated in the accompanying drawings, in which:

Fig. 1 is a vertical section of the furnace or heating chamber of the still.

Fig. 2 is a horizontal section of the same 40 on the line 2--2 of Fig. 1.

Fig. 3 is a vertical section on the line 3—3 of Fig. 1.

Fig. 4 is an enlarged view in elevation of a portion of the bank of tubes in the furnace 45 chamber, and

Fig. 5 is a similar view of the complete bank on the normal scale.

The enclosing walls of the device 1, are of the usual material employed for such purposes, and are built to include a fire chamber 2, a central vertical bridge wall 3, which divides the structure into two connected chambers or compartments. An oil or any other suitable fire may be used as the source 55 of heat.

In the second or rear chamber the front bank of tubes 4 is installed. These tubes, as above stated, are preferably of relatively small diameter and in the present instance 60 are arranged in five vertical rows, connecting at the bottom with a single header 5, in series by headers 6, and at the top to headers 7. These latter run to the nearest tube in the lowest row of the second bank of tubes 65 8 in the first chamber, and all of the tubes of

this bank are connected in series by headers 9, the horizontal rows being connected in series by the headers 10.

It will be observed that the bank of tubes in the first chamber is so located above the 70 level of the tubes in the rear chamber so that there is no possibility of the oil in flowing from one bank to the other being trapped and thereby injured by the heat.

The invention is not limited to any special 75 manner of connecting the tubes, as the connection whether in series or in multiple series or otherwise depends upon the viscosity of the oil and the amount of heating required.

The tubes of the first and preferably the second rows at the bottom of the bank of tubes in the first chamber are enveloped in corrugated cast-iron casings 11 of the well known Foster superheater type, and the 80 thickness of these casings or depth of the corrugations on such lower rows is less than that on the other rows, as is indicated in Figs. 1 and 3. The outlet for this second bank is shown at 12.

The cast-iron casings which as above set forth are preferably used on the tubes of both banks do not cover the entire length of the tubes, but the ends of these tubes are bare and over them are secured rectangular 95 plates 13 which, when the tubes are assembled, form the side walls of the heating chamber. The headers are connected to the projecting bare ends outside of the plates, as shown in Fig. 4. This is not a part of my 100 invention but is a valuable feature in devices of this kind.

The oil heated by this apparatus is introduced at 14 and passes up through the multiple series of small tubes 4 from the lower 105 to the upper headers. Thence it passes to the second bank of tubes and through all of these in series to the outlet header 12. Therefore, in the first bank, the flow of oil is counter to the flow of gases, while in the 110 second it is with such current, but the effect of this has been explained above.

It is not essential, though in some cases very desirable, that all the tubes in the first bank be arranged in multiple series, which latter arrangement reduces the resistance to the flow and secures a much more perfect heating effect, but otherwise the invention resides in the construction and arrangement hereinbefore set forth.

The parts of the device which I have not specifically described are or may be of the usual character and require no detailed description.

What I claim is:—

- 125
1. In an apparatus of the kind described, the combination of two heating chambers connected in series, a bank of tubes arranged in the chamber furthest from the fire, a second bank of tubes in the other chamber so 130

- disposed above the level of the bank in the first named chamber that oil in flowing from one bank to the other will not be trapped, the tubes in the first bank being connected so as 5 to secure a flow of oil counter to that of the hot gases, and the tube in the lowest row of the second bank being connected with the tubes of the top row of the first bank so that the oil from the first bank flows through them with the flow of hot gases.
- 10 2. In an apparatus of the kind described, the combination of two heating chambers connected in series, a bank of tubes arranged in the chamber furthest from the fire and connected with headers in series multiple, a 15 second bank of tubes in the other chamber all connected in series, said second bank of tubes being so disposed above the level of the bank in the first named chamber that oil in flowing from one bank to the other will not be trapped, an oil connection with the first bank whereby a flow of oil counter to that of the hot gases over said bank is secured, and a connection from the header of 20 the first bank to the lowermost row of the tubes in the second bank whereby the flow of oil in the said second bank is with that of the hot gases.
- 25 3. In an apparatus of the kind described, the combination with two heating chambers connected in series, of a bank of tubes in each chamber, so disposed at different levels that the oil in flowing from one to the other will not be trapped, connections whereby the 30 flow of oil in the bank furthest from the fire is counter to that of the hot gases, and in the second bank is with such flow and cast iron
- casings for all the tubes of said banks, the thickness of those casings on the tubes nearest the fire being less than that on the others. 40
4. In an apparatus of the kind described, the combination with two heating chambers connected in series, of a bank of tubes in the chamber furthest from the fire, a bank of tubes in the other chamber enveloped in cast 45 iron casings, such bank being so disposed above the level of the other that no trap for oil is formed in the connection between the banks, the casings of the tubes nearest the fire being of less thickness than the others, 50 and connections whereby the flow of oil in the tubes of the first named bank is counter to that of the hot gases, and in the other bank with such flow.
5. In an apparatus of the kind described, 55 the combination with a furnace structure having a vertical wall which divides the same into two heating chambers communicating with each other over the top of said wall, of a bank of tubes in each chamber, 60 said banks being so arranged at different levels that no trap for flowing oil is formed, the tubes in the chamber furthest from the fire being of relatively small diameter while those in the other chamber are of relatively 65 large diameter, all of said tubes being enveloped in cast iron casings and connections whereby the oil flow in the first named bank is counter to that of the hot gases and in the other bank with such flow. 70
- In testimony whereof I hereto affix my signature.

JOHN E. BELL.
